UNITED STATES PATENT OFFICE.

SAMUEL K. WELLMAN, OF CLEVELAND HEIGHTS, AND ALLEN A. GOULD, OF CLEVELAND, OHIO.

LUBRICATING APPARATUS.

Application filed February 19, 1925. Serial No. 10,344.

The invention relates to the commercial distribution and use of lubricants and has to do particularly with improvements in lubricating apparatus of the grease gun type.

5 One object of the invention is the provision of an improved process of packing and commercially distributing lubricant and applying it to bearings to be lubricated.

Another object of the invention is the 10 provision of an improved grease gun which the user can load and operate without any direct handling whatever of the lubricant, with the result that the apparatus is both convenient and cleanly in use.

15 A further object of the invention is the provision of a grease gun that can be very easily and quickly loaded with lubricant.

Another object of the invention is the 20 provision of an improved grease gun comprising a cartridge-like container for the lubricant which is adapted to serve as a convenient package in the commercial handling of the lubricant.

Other objects more or less incidental or 25 ancillary to the foregoing as well as the manner in which all of the various objects are attained will be apparent from the following description in connection with the accompanying drawings of the preferred 30 means for practicing our invention.

In the drawings:

Fig. 1 is a longitudinal section through a grease gun embodying our improvements.

Fig. 2 is a fragmentary side elevation of 35 the nozzle or discharge end of the grease gun shown in Fig. 1.

Fig. 3 is a longitudinal section through the lubricant cartridge or container removed from the body of the gun.

40 Fig. 4 is an outer end elevation of the said container.

Fig. 5 is an inner end elevation of the container.

Fig. 6 is an outer end elevation of the 45 movable end wall or piston of the container.

Fig. 7 is a side elevation of the side wall section of the lubricant container.

Fig. 8 is a longitudinal sectional view of a modified form of grease gun, some of the 50 parts being shown in side elevation.

Fig. 8^a is a fragmentary sectional view of the inner end of the lubricant cartridge shown in Fig. 8 with the frangible closure applied.

55 Fig. 9 is a longitudinal sectional view of

still another form of grease gun embodying our invention, some of the parts being shown in side elevation.

Fig. 10 is a longitudinal sectional view of the lubricant container shown in Fig. 10 but 60 with the end closure applied.

Fig. 11 is a longitudinal sectional view of another grease gun showing a slight modification of the form of grease gun shown in Fig. 9. 65

Fig. 12 is a longitudinal sectional view of the lubricant container shown in Fig. 11 with the end closure applied.

Referring in detail to the constructions illustrated and first to Figs. 1 to 7, 1 designates the chambered body or barrel of the grease gun. The body is tapered at 1^a toward its discharge end and is fitted with a nozzle or head 2. The nozzle 2 is fitted with a pump mechanism adapted to suck lubricant from the chambered body of the gun and force it from the end of the nozzle in a well-known manner. In so far as the present invention is concerned this pump mechanism may be of any suitable construction. 80 The specific form of pump mechanism shown is that of a commercially known grease gun and it will suffice to point out that it comprises a plunger 3 having a passage therethrough controlled by a spring pressed ball valve 4. 5 is a spring pressed check valve which controls the passage through a fixed abutment plate 6. A coil spring 7 is interposed between the abutment plate 6 and the plunger 3. The outer end of the nozzle 2 is 85 designed to engage a fitting of the bearing to be lubricated, such as shown at a. This fitting a is formed with diametrically opposite lugs or pins a', a', and the nozzle 2 is formed with opposite spiral slots 2^a, 2^b to engage the pins a'. In the use of the gun the nozzle 2 is engaged with the fitting a with the pins a' in the slots 2^a, 2^b. Then the gun is twisted about its longitudinal axis and this causes the end of the fitting a to press the plunger 3 toward the check valve 5 thus forcing lubricant past the ball valve 4 into the nozzle of the gun. On reversing the twisting movement of the gun, the spring 7 returns the plunger 3 to its normal position, 100 thereby exerting a suction on the lubricant tending to draw it from the body of the gun past the check valve 5.

As heretofore constructed this pump type of grease gun has had the lubricant intro- 110

duced directly into the body or barrel of the gun and has been fitted with a piston-like follower so that when the lubricant at the inner or nozzle end of the gun is subjected to suction, atmospheric pressure on the follower forces the lubricant forward toward the nozzle end of the gun. In carrying out our present invention we do away entirely with the follower engaging the inner walls of the barrel of the grease gun, and instead of introducing the lubricant into direct engagement with the body of the grease gun we enclose the lubricant in a cartridge-like container which is introduced bodily into the barrel of the grease gun. As shown in Figs. 1 and 3 to 7, inclusive, this container, designated in its entirety by 8, comprises a tubular side wall 9, said wall preferably consisting of an inner tube 9^a and a shorter outer tube 9^b. The inner or discharge end of the container is formed by a frustro-conical cap or closure 10 which fits the end of the inner tube 9^a as shown. The cap 10 has a central aperture 10^b which, before the container is inserted in the gun is closed by a removable or frangible seal 11. The outer end of the cartridge or container is formed by a piston-like member 12 which has a cylindrical wall section or skirt 12^a which fits within the side wall 9 with just sufficient clearance to permit the member 12 to move piston-like within said side wall without allowing leakage of lubricant. The skirt 12^a of the piston 12 is preferably braced or strengthened by a disk 12^b secured therein. In addition to the piston or follower 12 the cartridge has at its outer end a closure or cap 13 which fits the end of the side wall tube 9^a. The cap 13 has a central aperture 13^a which, before the cartridge is inserted in the gun is sealed by a removable or frangible seal 14.

While our invention is not limited to the use of any particular material for the lubricant cartridge or container, as any oil-proof material adapted to give the cartridge a suitable amount of rigidity can be employed, we prefer in the interests of low cost and light weight to use an oil-proofed paper or fibrous material of suitable thickness. The oil proofing of the fibrous material is preferably effected by a treatment with silicate of soda or lacquers having a cellulose base, though we do not limit our invention to the use of these or any other materials for the treatment. The cartridge can of course be formed of sheet metal but, as above indicated, lower cost is attainable by the use of the suitably treated fibrous material. Furthermore, the latter material provides a resiliently flexible side wall for the cartridge that cannot easily be so dented or deformed that the piston-like end wall 12 will not readily move therethrough.

The outer open end of the gun barrel is normally closed by a cap 15 which is detach-

ably secured to the barrel of the gun by bayonet slot connections comprising slots 15^a formed in the flange of the cap and pins or lugs 16 carried by the gun barrel. The construction is such that when the lubricant container 8 is inserted in the barrel of the gun and the cap 15 is applied said cap forces the container inward and effects a substantially air-tight annular seal at 17 between the inner conical end of the container and the adjacent tapering wall 1^a of the body of the gun.

From what has been said in the foregoing description the nature of our improved process and the operation of the apparatus will readily be understood. Lubricant of suitable quality, that is to say, an oil or grease that will not cake and harden, is filled into the cartridges at the factory under mass production conditions where systematic cleanly methods avoiding waste of lubricant are feasible. The loaded cartridge, in the form illustrated in Figs. 3, 4 and 5, is then readily handled, packed and shipped in the regular course of commercial distribution.

The user of the lubricant, being supplied with the grease gun illustrated in Figs. 1 and 2, purchases the lubricant-filled cartridges from the retailer and in the use of the grease gun it is only necessary for the operator to remove the cap 15 and insert one of the lubricant cartridges, having first however pulled off or broken the seals 11 and 14. When the cartridge is inserted in the gun barrel, the cap 15 is replaced and in so doing a substantially air-tight seal is effected at 17 as above described.

With the grease gun loaded it is only necessary for the operator to apply it to a bearing fitting such as that indicated at a and actuate the pump mechanism by a back and forth twisting movement, in order to create a suction which by reason of the atmospheric pressure back of the piston or follower 12 results in the latter moving forward in the cartridge to feed the lubricant forward to the pump mechanism. As use of the gun is continued the piston or follower 12 continues to advance toward the discharge end of the gun and finally completely empties the cartridge, the piston 12 being shaped to conform to the shape of the front or inner end of the cartridge so as to effect such complete emptying.

In the operation of the apparatus as described, the cylindrical skirt 12^a of the piston 12, while having sufficient freedom for movement in the tubular wall of the cartridge, nevertheless effects a substantially air-tight fit with said wall, the lubricant assisting to effect the seal. The skirt 12^a of the piston is of course made of suitable length so that no binding occurs which is not readily overcome by the atmospheric pressure on the piston.

When a cartridge has been emptied of lubricant by use of the gun as above described, the gun is very easily reloaded by simply detaching the cap 15, removing the 5 empty cartridge and inserting a full one in the manner previously described. After the gun has been placed in use the forward neck portion of the gun between the discharge end of the cartridge and the stationary 10 check valve of the pump mechanism becomes filled with lubricant so that when a full cartridge of lubricant is inserted in the gun the latter is in condition to at once discharge lubricant from the nozzle without any preliminary actuation of the pump mechanism to effect "priming". In putting the grease gun to use in the first instance the user may prefer to introduce a small amount of lubricant into the neck of the gun ahead of the 15 cartridge to facilitate priming.

In Figs. 8 and 8^a we have illustrated a modified form of grease gun embodying our invention. In this latter form of construction the grease gun has a body or barrel 21 with a relatively flat conical end 21^a and cylindrical neck 21^b. To the neck 21^b is attached a nozzle 22 containing pump mechanism precisely like that illustrated in Fig. 1. The cartridge 23 employed in this instance is substantially the same as that illustrated in Fig. 1 except that the cap 24 closing the discharge end of the cartridge is not as deep as that of the cartridge shown in Fig. 1 but is formed with a frustro-conical 25 annular portion 24^a which is shaped to provide an annular engagement of substantial width with the adjacent wall of the gun body thus insuring more fully perhaps an adequate air-tight seal between the inner end 30 of the cartridge and the adjacent wall of the gun body. The cartridge in this second form of construction is further and correspondingly modified in that the piston 25 is shaped to conform to the cap 24 of the cartridge.

The open end of the gun barrel in this second construction is closed by a cap 26 secured by bayonet couplings 27 as in the first form of construction but in this second construction the cap 26 is made somewhat deeper and carries a resilient packing ring 28 of rubber or the like which, when the cap is applied to the gun barrel, is compressed between the cap on the one side and the ends 35 of the gun barrel and of the cartridge on the other side. The result is that an annular air-tight seal is effected between the end of the cartridge and the end of the gun barrel, this latter seal serving simply to supplement that at the inner end of the cartridge or, in other words, to double insure the air-tight seal between the cartridge and the gun body which is essential to the operation of the device.

65 We prefer a cartridge of the form shown

in Fig. 8 to that shown in Fig. 1 for the reason that the cap at the discharge end of the cartridge and the forward part of the piston, being more shallow, are more readily formed.

70

It will be understood of course that the cartridge shown in Fig. 8 is provided at its ends with seals such as that at 24^b, Fig. 8^a, these seals, as in the case of the first construction, being torn off or punched when 75 the cartridge is inserted in the barrel of the gun.

75

In Figs. 9 and 10 we have shown another form of construction in which the body 31 and nozzle 32 are precisely the same as that shown in Fig. 1. The cartridge 33, however, is designed to have the cap 34 which closes its discharge end entirely removed before the cartridge is inserted in the gun. Thus, as indicated in Fig. 9, the end 35 of 80 the side wall of the cartridge is forced into sealing engagement with the wall of the gun body when the cartridge is in working position in the gun.

80

The gun barrel is fitted in this case with 85 a cap 36 secured by bayonet coupling 37 and provided with an air-tight resilient packing 38 just as in the case of the construction shown in Fig. 8. Consequently when the gun is loaded and the cap 36 attached, air 90 tight seals are effected between both ends of the cartridge and the barrel of the gun. The cap at the outer end of the cartridge is apertured and provided with a seal 39 as in the other forms of construction already described, the seal 39 being removed when the cartridge is inserted in the gun so that the atmospheric pressure is freely exerted against the piston 40 of the cartridge when suction is created by the pump mechanism. 95

100

In Figs. 11 and 12 is illustrated a slight modification of the construction shown in Figs. 9 and 10, the difference residing entirely in the form of the side wall of the cartridge at the discharge end thereof. In this 110 latter construction the side wall has its end turned slightly inward to form a narrow flange 41 which engages the adjacent inner wall of the gun body when the latter is loaded as indicated in Fig. 11. The in-turned flange is provided to engage the piston 42 of the cartridge when the latter is 115 completely empty and insure withdrawal of the piston when the cartridge is removed from the gun.

120

It will be understood that the forms of construction illustrated in Figs. 8, 9 and 11 operate in substantially the same manner as the construction illustrated in Fig. 1 and that in each case the advantages of our improved processes are realized.

125

Briefly summarized the advantages of our improved process and apparatus are the avoidance of the waste of lubricant and the mussiness incident to filling the old-style 130

4
grease guns with lubricant, and the extreme ease and convenience with which our improved grease gun can be filled or loaded with lubricant.

5 These advantages are, of course, attained by the use of the cartridge-like lubricant container which satisfactorily serves the added purpose of holding the lubricant for commercial distribution.

10 The present application constitutes in part a continuation of our earlier filed application Serial No. 752,039.

15 While we have illustrated the preferred manner of carrying out our invention it will be understood that there can be variations in various respects without departing from our invention as defined in the appended claims.

What we claim is:

20 1. In a lubricant gun, the combination of a chambered body; a discharge nozzle for one end of the body; a cartridge-like container for lubricant removably mounted in the chambered body, said container having a 25 lubricant discharge opening at its inner end adapted to be covered by a substantially liquid-tight closure when the container is out of the chambered body and comprising a tubular side wall and a piston-like outer 30 end wall exposed on its outer side to atmospheric pressure and adapted to move within the tubular side wall; means associated with the nozzle for sucking lubricant from the container and forcing it out of the nozzle; and means for maintaining a substantially 35 air-tight joint between the wall of the container and that of the chambered body to prevent passage of air between said walls to the said suction means.

40 2. In a lubricant gun, the combination of a chambered body; a discharge nozzle for one end of the body; a cartridge-like container for lubricant removably mounted in the chambered body, said container having a 45 lubricant discharge opening at its inner end adapted to be covered by a substantially liquid-tight closure when the container is out of the chambered body and comprising a tubular side wall and a piston-like outer end 50 wall exposed on its outer side to atmospheric pressure and adapted to move within the tubular side wall; means associated with the nozzle for sucking lubricant from the container and forcing it out of the nozzle; and means for maintaining at the discharge end 55 of the container a substantially air-tight joint between the wall of the container and that of the chambered body to prevent passage of air between said walls to the said suction means.

3. In a lubricant gun, the combination of a chambered body; a discharge nozzle for one end of the body; a cartridge-like container for lubricant removably mounted in

the chambered body, said container having a 65 lubricant discharge opening at its inner end adapted to be covered by a substantially liquid-tight closure when the container is out of the chambered body and comprising a tubular side wall and a piston-like outer 70 end wall exposed on its outer side to atmospheric pressure and adapted to move within the tubular side wall; means associated with the nozzle for sucking lubricant from the container and forcing it out of the nozzle; and a removable closure for the outer end of the body of the gun engaging the adjacent end of the lubricant container and forcing the inner end of the container against the wall of the gun to effect 75 a substantially air-tight seal between the walls of the container and the body of the gun, respectively, to prevent passage of air between said walls to the said suction means.

4. In a lubricant gun, the combination of a chambered body; a discharge nozzle for one end of the body; a cartridge-like container for lubricant removably mounted in the chambered body, said container having a lubricant discharge opening at its inner 85 end adapted to be covered by a substantially liquid-tight closure when the container is out of the chambered body and comprising a tubular side wall and a piston-like outer 90 end wall exposed on its outer side to atmospheric pressure and adapted to move within the tubular side wall; means associated with the nozzle for sucking lubricant from the container and forcing it out of the nozzle; a removable closure for the outer 95 end of the body of the gun; and a packing ring clamped between the closure and the outer ends of the gun body and the container to effect a substantially air-tight seal between the body of the gun and the wall of 100 the container substantially as and for the purpose set forth.

5. In a lubricant gun, the combination of a chambered body; a discharge nozzle for one end of the body; a cartridge-like container for lubricant removably mounted in the chambered body, said container having a lubricant discharge opening at its inner 110 end adapted to be covered by a substantially liquid-tight closure when the container is out of the chambered body and comprising a tubular side wall and a piston-like outer 115 end wall exposed on its outer side to atmospheric pressure and adapted to move within the tubular side wall; means associated with the nozzle for sucking lubricant from the container and forcing it out of the nozzle; a removable closure for the outer end of the body of the gun; and a packing ring interposed between said closure and the outer ends of the gun body and the container, the removable closure being adapted 120 to exert pressure through said packing ring 125

to effect substantially air-tight joints between the walls of the gun and both the inner and outer ends, respectively, of the lubricant container substantially as and for the purpose set forth.

6. In a lubricant gun, the combination of a chambered body; a discharge nozzle for one end of the body; a cartridge-like container for lubricant removably mounted in 10 the chambered body, said container having a lubricant discharge opening at its inner end adapted to be covered by a substantially liquid-tight closure when the container is out of the chambered body and comprising 15 a tubular side wall and a piston-like outer end wall exposed on its outer side to atmospheric pressure and adapted to move within the tubular side wall; means associated with the nozzle for sucking lubricant 20 from the container and forcing it out of the nozzle; and means for maintaining a substantially air-tight joint between the wall of the container and that of the chambered body to prevent passage of air between said 25 walls to the said suction means, the inner end of the lubricant container being formed to engage the piston-like end wall thereof and insure withdrawal of said end wall

from the gun when the empty container is removed therefrom.

30

7. In a lubricant gun, the combination of a chambered body; a discharge nozzle for one end of the body; a cartridge-like container for lubricant removably mounted in the chambered body, said container having 35 a lubricant discharge opening at its inner end adapted to be covered by a substantially liquid-tight closure when the container is out of the chambered body and comprising a tubular side wall of resiliently flexible 40 material and a piston-like outer end wall exposed on its outer side to atmospheric pressure and adapted to move within the tubular side wall; means associated with the nozzle for sucking lubricant from the 45 container and forcing it out of the nozzle; and means for maintaining a substantially air-tight joint between the wall of the container and that of the chambered body to prevent passage of air between said walls 50 to the said suction means.

In testimony whereof, we hereunto affix our signatures.

SAMUEL K. WELLMAN.
ALLEN A. GOULD.
